DRILL GUIDE FOR TEMPLATE DRILLING

Joseph Basta, Westbury, N. Y.

Application March 6, 1944, Serial No. 525,325

5 Claims. (Cl. 77—55)

This invention relates to improvements in drill guides for template-drilling.

In template drilling, the drill, which is mounted in a suitable chuck supported in a drill-head, must in the normal operation of drilling be inserted in and pass through the bore of a standard or conventional tip which, in said operation is, in turn, suitably positioned and guided in the template. After each drilling operation is completed, the drill is removed or withdrawn from said bore of the tip by the operator and held in elevated position in relation to the tip until the next drilling operation, when it is again moved downwardly, inserted and passed through said bore of the tip.

It is desirable, in order to assist the operator in speedy and accurate production, that the insertion and removal movements of the drill be guided so that when the drilling-head is moved downwardly by the operator in the act of drilling, the drill will be guided to enter the bore of the tip in a line co-axial with the bore of said tip and that, upon completion of a drilling operation, the drill will, upon release of pressure on the head by the operator, be automatically lifted and guided in its removal movement from said bore.

Heretofore, certain devices have been used for the purpose specified which comprised expandable and contractible spiral springs, but such devices have not been satisfactory or efficient in the performance of the necessary functions, and it is the primary object of my invention to provide a drill-guide that will perform its necessary guiding functions in a more satisfactory manner, both in the insertion and removal movements of the drill; that will provide greater accuracy of said guided movements of the drill over prior-art devices; and that will provide greater visibility of such movements for the operator.

Another object is to provide increased contraction and expansion of the guide, to permit use of greater lengths of drills, and consequently to permit drilling of an increased number of sheets of metal in one operation.

Other objects of my invention are: to utilize a drill-guide comprising a longitudinally-contractible and expandable cage-like structure having a body portion formed of spring slats spaced from each other and surrounding a common axis so that the drill positioned at said axis will be visible and accessible at all times during the drilling operation; to provide means whereby, during the guided drill-insertion and drill-withdrawal movements, the spring-retarding and guiding actions will be substantially constant and uni-

form; to provide means whereby an initially-bent section of the cage-like structure will function as a guide for the starting and subsequent contracting movements of the device; and to provide an arrangement of the spring slats that, during the drill-insertion movement will cause them to spread outwardly to provide greater visibility and accessibility of the drill to the operator, while in the withdrawal movement and in withdrawn, elevated position, the drill guide will still permit sufficient and satisfactory visibility and accessibility for adjustments and renewals that may be required; to provide a device that will be strong and durable, simple in construction, positive in operation, economical to manufacture, that will not be likely to get out of order and that when not in use will maintain its normally-operative position and act as a guard for the drill.

With the above and other objects in view, the invention comprises the combination of members and arrangement of parts so combined as to coact and co-operate with each other in the performance of the functions and the accomplishment of the results herein specified, and comprises in one of its adaptations the species or preferred form illustrated in the accompanying drawings, in which:

Fig. 1 is a view in front elevation of a drill guide embodying my invention;

Fig. 2 is a top plan view of the upper fastening and spring-guiding ring of my drill-guide;

Fig. 3 is an edge view of one of the spring slats embodied in my drill-guide;

Fig. 4 is a view in elevation of the slat shown in Fig. 3;

Fig. 5 is a plan view of the lower ring of my said drill-guide;

Fig. 6 is a view in side elevation of the ring shown in Fig. 5;

Fig. 7 is a view similar to Fig. 6 with a part of the wall broken away to show the tapped internal bore; and

Fig. 7a is a view, in side elevation, of a standard or conventional tip, shown separated from the mounting ring, and turned one-quarter of a revolution from the position of said tip shown in Fig. 1.

Referring now to these drawings, 1 indicates a non-rotatable collar or drill-head having a chuck 2 in which is mounted a drill 3, and 4 shows a standard or conventional tip having a tapered body portion 4' merging with a cylindrical terminal portion 5 adapted to fit an opening in a template or pattern and said tip is provided with the usual axial bore and a communicating hori-

zontal kerf 6' and also has at its upper end a screw-threaded connection for mounting in a suitable holder. All of the above members are of standard and conventional form and construction and constitute no part per se of my invention.

In accordance with the preferred form of my invention illustrated in Figs. 1 to 7a, my drill-guide comprises a resilient spring body portion of substantially inverted bell-shaped configuration and constitutes a longitudinally contractible and expandable cage-like structure formed of a plurality or series of laterally-spaced, preformed spring plates or slats so arranged as to permit an outward bellying or spreading movement in the plane of their longitudinal axes when pressure is applied at their upper ends. Said slats or plates are supported at their top and bottom ends to provide said cage-like structure that is capable as a whole of contraction and expansion along a longitudinal axis by a spreading outwardly from and a movement inwardly toward said longitudinal axis. As illustrated, said cage-like structure is composed of an upper circular supporting member 10 of a diameter capable of fitting over a drill-head, a lower circular supporting member 14 of lesser diameter, and a plurality or series of identical intermediate plate or slat spring members 16 spanning in length a vertical space between the supporting members and laterally spaced from each other to produce said vertically-slatted cage-like structure which when mounted on a drill-head will house the drill and cause it to extend co-axially within the same and will guide the drill, when the head is depressed manually or otherwise, to move along the axial line of the cage and into the bore of the conventional tip when the same is suitably mounted in said drill guide.

The upper supporting member 10 comprises as shown a split ring adapted to encircle and be fastened to a drill-head in such manner that the drill and chuck extend axially within said body or cage-like structure. As shown, the member 10 is split at its terminal ends 11 and a screw 12 is arranged to connect said ends and draw them together to fasten said supporting member on the drill-head 1. Said supporting member 10 is, as shown, provided with three symmetrically-arranged notches 13 which provide seats for the top ends 16b of the slats. These top ends are reduced in width to fit said notches and are fastened therein to the said supporting ring 10 by bolts 17.

The lower ring 14 preferably comprises a hollow sleeve and is provided with notches 15 forming seats for the lower ends 16c of the slats 16. These lower ends are similarly reduced in width and are securely fastened to the sleeve within said seats by bolts 18.

Each of the slats, as shown, have upper portions 16' that, in unexpanded or normal condition, is provided with an initial or starting bend comprising an outward curvature or elliptical bend so as to enable an initial easy contracting movement and a similar easy outward bellying or resilient movement of said members 16 when the

head is depressed in the drilling operation. In such outward bellying movement, the lower portion 16a moves less than the upper section and the lower ends act like fulcrums to enable the drill to be moved axially within said drill-guide body or cage-like structure.

The hollow sleeve or ring 14 has, as shown in Fig. 7 a tapped bore 19 and the threaded end 20 of the conventional tip 4 is mounted in said tapped bore 19 with its bore 6 in co-axial alignment therewith.

In operation, it will be clear from the above that downward pressure exerted on the head either manually or otherwise, will cause the drill shown in dotted lines in Fig. 1 to be guided in its downward movement along the axis of the drill-guide body and into and through the bore 6 of the tip for a drilling operation, and that when such drilling operation is completed, and downward pressure on the head is relieved, the drill again will be automatically guided axially to the approximate elevated position within the drill-guide body shown in Fig. 1.

Having described my invention, I claim:

- 25 1. A drill guide comprising a longitudinally-contractible and expandable cage-like structure having a body portion formed of a plurality of longitudinally-extending resilient slats spaced from each other and surrounding a given axis, and holder means at opposite ends of said slats for fastening and retaining said slats in said cage-like structure.
- 30 2. A drill-guide as specified in claim 1 in which the cage-like structure has an initially-bent section for facilitating the starting and subsequent contracting and expanding movements.
- 35 3. A drill guide comprising a longitudinally-contractible and expandable cage-like structure having a body portion formed of a plurality of longitudinally-extending resilient slats spaced from each other and surrounding a common axis, and holder means at opposite ends of said slats for fastening and retaining said slats in said cage-like structure, each of said slats having an upper section provided with an outwardly-bowed elliptical bend.
- 40 4. A drill-guide as specified in claim 3 in which the holder means is composed of circular top and bottom members, and the circular bottom member is of much smaller diameter than the upper member, and each has seats for mounting the opposite ends of the resilient slats.
- 45 5. A drill guide comprising a longitudinally-contractible and expandable cage-like structure having a body portion formed of a plurality of longitudinally-extending resilient slats spaced from each other and surrounding a common axis, and circular top and bottom members provided with seats for mounting the opposite ends of the resilient slats, means for fastening said slats in said seats, the bottom member comprising a tapped sleeve for the reception of a template drilling tip and being of much smaller diameter than the upper circular top member.

JOSEPH BASTA.
